UNITED STATES PATENT OFFICE

1,973,218

GASOLINE ENGINE STARTER

John Mikulasek, Newton, Iowa, assignor to The Maytag Company, Newton, Iowa, a corporation of Delaware

Application September 27, 1929, Serial No. 395,518

3 Claims. (Cl. 74—6)

The present invention relates to a novel construction of a two cycle gasoline engine or motor which is provided with a single horizontal cylinder, and although the engine is of general application, it is particularly adapted for washing machines and similar uses where a small independent power plant is desired.

Among the objects of the invention are to provide a novel construction of gasoline or internal combustion engine, which is unique in design, size and compactness, and one which is admirably adapted for any use where a small power plant is desired.

A further object of the invention is to provide a novel construction of starting clutch and foot lever adapted to start and accelerate an engine by treading on the foot lever and transmitting the movement to the crank shaft of the engine through positive and direct acting, engaging and disengaging mechanism. By this construction, the shaft is turned over by manually operating and direct acting means for producing the necessary acceleration.

Another object of the invention is to provide a carburetor construction in which the fuel is drawn from the fuel tank in the base or lower portion of the engine and through the lubricant in the crank case. This arrangement prevents flooding. The fuel is drawn into the carburetor by the same suction which also draws in the air for forming a combustible mixture, the amount of air which is sucked into the carburetor remaining constant, while the amount of fuel can be adjusted for obtaining the proper mixture for carburetion and smooth running of the engine.

A further object of the invention is to provide a novel means and method of lubrication in which the lubricant is mixed with the fuel in the fuel tank, and then carried through the carburetor into the engine and deposited on all wearing surfaces of the engine. This fuel is forced by the reciprocating suction and compression action prevailing in the crank case, through the cylinders, piston, connecting rod, bearings, wrist pin, etc. By this means and method of lubrication, all wearing parts of the engine construction are continuously and positively oiled.

Another object of the invention is to provide a novel means and method of ignition in which the magneto is provided with a positive timing mechanism and is adapted to generate a spark in but one direction of rotation of the fly wheel. The system of ignition is governor controlled, and the operating parts are reduced to a mini-

mum, thus providing a simple and efficient method of ignition.

A still further object is to provide a fly wheel magneto in which the fly wheel assembly has thereon means for circulating air for cooling the engine, the engine being provided with heat radiating ribs or fins which in combination with the fly wheel, dissipate the heat from the cylinder wall and other portions of the engine.

Another object of the invention is to provide a novel construction of crank shaft and gasoline engine. Further objects are to provide an engine of maximum simplicity, efficiency, economy and ease of assembly, operation and repair; and such further objects, advantages and capabilities as will later more fully appear and are inherently possessed thereby.

The invention further resides in the combination, construction and arrangements of parts illustrated in the accompanying drawings, and while I have shown therein a preferred embodiment, it is to be understood that the same is susceptible of modification and change, and comprehends other details, arrangements of parts, features and constructions, without departing from the spirit of my invention.

In the drawings:

Fig. 1 is a view in side elevation of the engine.

Fig. 2 is a view in front elevation of the construction disclosed in Fig. 1.

Fig. 3 is a view in horizontal cross section taken on the line 3—3 of Fig. 2.

Fig. 4 is a view in vertical cross section of the foot lever and starting clutch, taken on line 4—4 of Fig. 3.

Fig. 5 is a fragmentary view in side elevation of the magneto and fly wheel.

Fig. 6 is a view in vertical cross section of a fragment of the engine and crank case, and disclosing the construction of the carburetor.

Fig. 7 is a view in vertical cross section through the cylinder.

Referring more particularly to the drawings, the engine construction is mounted upon a casting providing a fuel tank 1, the casting being provided with frame extensions 2 and 3 for mounting the same upon a washing machine or other driven means for which this power plant may be used. The fuel tank is provided with a filling opening 4 adapted to be closed by a threaded plug 5 which is mounted in the upper portion of the fuel tank so that the same may be filled only to the top of the opening. The bottom of the tank is provided with a pet cock 6 for draining and cleaning the fuel tank. The top of the fuel tank

95

100

105

110

is provided with a cover plate 7 having a lug 8 on its upper surface and is further provided with necessary bolt holes to support a crank case 9. The plate is further provided with an opening in 5 its upper surface to accommodate the fittings of a carburetor.

The crank case 9 provides the housing for a crank shaft 10 and connecting rod and furnishes a direct support for one end of the crank shaft 10 and provides connection for a main double bearing 11, cylinder 12, and carburetor 13. One end of the cylinder is in full communication with the crank case and the other end receives its communication with the crank case by means of an intake port 14 for an instant during every revolution of the fly wheel. An exhaust port 15 is provided in the lower part of the cylinder for disposing of the burnt gases.

In order to properly start and accelerate the 20 engine, I have provided a novel construction of foot starter, which operates directly on the crank shaft 10. Mounted on the crank shaft 10, I provide a cup-shaped ratchet wheel or clutch member 16 provided with relatively deep internal pockets 17 for receiving balls 18.

Adjacent to this ratchet wheel is provided a cam pinion 19 loosely mounted on the shaft 10. The cam portion 20 of the pinion projects into the cup of the ratchet wheel 16 and is provided with shallow pockets 21 for the balls 18 to shoulder. Both the pockets 17 in the ratchet wheel, and the pocket 21 in the cam, are shaped edgewise and will interlock with the balls that fall between them, thus transmitting power from the cam pinion to the ratchet wheel or clutch member in the direction required for starting of the engine. If, however, the cam is rotated in the opposite direction, the balls will be shifted from the interlocking position by reason of the negative slant 40 of the pockets and forced out of the way into the deep cavity of the pockets 17 so that the two coupling members remain free from engagement during certain periods in the starting and during all the time when the engine is running. While the engine is running, these balls are kept in the deep pockets or cavities 17 by reason of centrifugal force of the rotating shaft.

The member 19 is provided with a pinion gear 22 adapted to mesh with an arcuate gear segment 50 23 pivoted on a stub shaft or pin 24 and adapted to be operated by means of a foot lever 25. A tension spring 26 functions to retract the segment to its inoperative position. In order that the foot lever may be pushed out of the way of the operator when not in use, it is pivotally fastened to the hub of the arcuate gear 23 and coupled with the segment by means of a pair of clutch jaws 27. A rod or bar 28 provides a stop means against which the lever 25 impinges in its lowest position.

Movably mounted on the gear segment 23 is 60 provided a yieldable gear tooth 23a. In the neutral position shown in full lines in Fig. 4, the gear segment is out of and beyond engagement with the teeth on the pinion gear 22, allowing this pinion gear to rotate freely with the crank shaft, and thus eliminating all friction with the shaft and the care of lubrication which this pinion gear 22 would require were it left in engagement with 65 the segment during the operation of the engine. Furthermore, should the engine backfire, no gear teeth would break since they would clear engagement before the foot lever could strike the cross bar 25a. Were the initial tooth or teeth 70 of the gear segment rigid, there would be the

possibility of the teeth of the gear segment locking with those of the pinion gear when they were first brought into mesh. This locking of the teeth happens frequently, even though the teeth are pointed or otherwise shaped.

In order to make the tooth 23a yieldable, the same is formed on a plate a having elongated slots b in which are mounted bolts c engaging the gear segment 23. The slots b are of greater length than the diameter of the bolts c so as to allow for a longitudinal movement of the plate a and tooth 23a. A spring d fitting in a slot in the plate a, normally holds the plate and tooth in distended position where it is adapted to engage the teeth of the pinion gear 22.

In the present construction, the yielding tooth slips from the points of the pinion gear teeth into the nearest tooth spaces and insures proper and smooth meshing of the teeth, and eliminates completely the objectionable shock which the operator received by the unexpected locking of the gear teeth of prior constructions.

A friction plug 29 is inserted in a boss 28 in the hub of the foot lever 25 so as to hold the foot lever in upright bolted position. In order to prevent 100 injury to an operator, the arcuate gear segment is provided with a safety guard 30, while a guard 31 encloses the ratchet wheel 16.

The crank shaft 10 is of the central type, the side to which is mounted the foot starter, is 105 shorter in length than the other side. This longer side transmits a working torque load of the engine and carries a fly wheel magnet 32 and a drive pulley 33 mounted upon a coupling disc 34, which in turn is mounted on a cup-shaped housing 32a of the fly wheel. This coupling disc is connected to the end of the crank shaft by being forced over the tapered portion 35 of this shaft, and held in place by means of a nut 36. A key 37 holds the disc or torque plate in proper angular 110 relation with the crank shaft for the purpose of timing the magneto.

Three separate bearings, one of which numbered 38, is on the short side of the crank shaft, and two numbered 39 and 40, are on the long side 115 of the crank shaft for supporting the same. The bearings adjacent the crank 41 take the main shaft load delivered to the crank shaft through the connecting or piston rod 42. The outer bearing 40 carries principally the load exerted 120 by the pull of the belt or the pulley and by the energy of the fly wheel. In order to provide smooth running of the engine, the crank shaft is balanced by means of a lug or lugs 43 on the ratchet wheel 16 and a lug 44 on the coupling disc 125 34, these lugs acting as counter-weights and are so positioned as to be in proper relation with the bend of the crank shaft.

The connecting or piston rod 42 is connected to a sliding piston 45 adapted to slide in the cylinder 130 12. As clearly shown in the drawings, the cylinder is in a horizontal position. The engine being of the two cycle construction, the intake and outlet ports are opened by the sliding piston 45 at the end of each rearward stroke of the piston, the exhaust port being opened a trifle earlier than the intake port. This prior opening of the exhaust port causes the burned gases to escape from the cylinder and permit a new charge of fuel mixture to enter the cylinder. The piston 135 on its rearward stroke will compress the fuel mixture in the crank case sufficiently to cause the vaporized fuel to rush through the intake port into the explosion chamber. In order to prevent this fresh charge from blowing out of 140 150

the cylinder through the simultaneously opened exhaust port, located on the opposite side from the intake port, a deflector 46 is provided on the piston directly in front of the intake port. By 5 means of this construction the charge is deflected and before it has time to again rush towards the exhaust port, both the exhaust port and the intake port are closed and the new charge is compressed, ready to be ignited at the 10 end of the compression stroke.

While the piston is compressing the combustible mixture, the opposite end of the piston forms a vacuum in the crank case, and more gas mixture is drawn into the carburetor to be again 15 compressed in the crank case on the power stroke of the piston, to enter the firing chamber when the intake port opens again. The exhaust gases passing through the exhaust port 15 are led through an elbow 47 and then through a flexible 20 metal hose 48 to be disposed of as desired, either through a muffler or otherwise.

The carburetor 13 comprises a rectangular housing 49 provided with an upper air intake 50 having a filter screen 51. The carburetor proper 25 is divided into two compartments, an upper compartment or air chamber 52 and a lower compartment or mixing chamber 53. The air entering the air chamber through the filter 51 is admitted into the mixing chamber through a check valve 54 which is opened and closed by the suction and 30 compression created by the piston 45 of the engine through the communicating crank case 9. The check valve is provided with a stem 55 guided in an opening 56 in a threaded cap 57. A spring 35 58 in the opening 56 holds the valve 54 seated with the bushing 59. The inrushing air through this valve during the suction period is met by a spray of gasoline or other fuel sucked in at the same 40 time through an adjustable jet 60. The fuel passing through this jet is drawn from the fuel tank below through a strainer and check valve 61, through the feed tube 62 to the jet 60. This fuel is drawn by the same suction of the engine as that which draws the air through the valve 54 into the mixing chamber. The purpose of the 45 check valve 61 is to hold the fuel in constant level since the column of fuel in the feed tubing is subjected to alternate reciprocating suction and compression. The amount of fuel allowed to enter the engine is regulated by a needle valve 63 adapted to be adjusted by means of a handle 64. In order to prevent the needle valve from slipping or changing its position due to vibration or other causes, the same is provided with a spring 65 seated between the carburetor housing and the handle 64. This construction does not depend upon any prevaporized fuel being formed ahead of the intake valve. It further eliminates the use of any injector. Since the alternate suction and compression causes the check valve 61 to be 50 opened and closed, there is no possibility of this valve sticking.

Since the gasoline or other fuel in the tubing 62 and likewise in the jet 60 is subjected to periodical momentary compression, it frequently happens that some of the gasoline is forced by threads of the needle valve by this pressure. In order to return this fuel to the fuel tank, a small tube 66 is provided. A tube 67 provides a vent for the 65 fuel tank. This tube leads into the air chamber 52 of the carburetor, and any escaping vapor from the supply of the gasoline is thus caught by the carburetor and sucked into the engine.

In order to properly position the carburetor on 70 the engine, the same is provided with flanges 68

adapted to contact with and be connected to a side of the engine. Flanges 69 are also provided on the bottom of the carburetor housing, the horizontal and vertical flanges forming a cover over the assembly wall of the crank case and the 80 fuel tank.

The purpose of the carburetor is to mix the air with a proportionate amount of fuel and deliver to the engine at the bottom surface of the crank case housing. This feature is extremely important for the proper running of the engine, for the reason that the inrushing vapor will agitate and mix with the heavier fuel in the bottom of the crank case and thus keep the same from flooding. For this reason, the present engine is 85 not provided with any deflooder at the base of the crank case, and thus there is no means to clog and flood the engine, as has been the case where deflooders have been provided.

Furthermore, the present construction does 90 away with any contamination of the fuel. There is no possibility of the humid air securing access to the fuel tank to cause accumulation of water in the gasoline. With the new carburetor and its arrangement, the fuel in the tank is not affected. 95 There is but one adjustment from the carburetor, the air remaining constant while the amount of fuel may be adjusted to obtain a proper mixture. This adjustment is accomplished by means of the arm or handle 64 operating on the needle valve. 100 When this handle is moved in a clockwise direction, the needle valve is closed, while when the same is moved in a counter-clockwise direction, the needle valve is opened.

The lubrication of the engine, bearings and all 105 other working parts of the engine is accomplished by mixing the lubricating oil with the fuel in the fuel tank, this lubricant being carried through the carburetor into the engine in vapor form with the fuel and there deposited on all wearing surfaces of the engine. The reciprocating suction and compression action of the engine draws the lubricant from the crank case and forces the same through all the bearings, wrist pin, cylinder, etc. To facilitate better circulation of the lubricant 110 in the bearings, these bearings are provided with oil grooves, oil holes and notches.

In order to avoid the forcing of any of the lubricant through the bearings and therebeyond, by the compression force in the crank case, the 115 bearing 38 on the short side of the crank is provided with a felt washer 70 placed in an interlocking groove between the end of the bearing and the ratchet wheel 16.

The bearing 40 is provided with a lubricant deflecting device whereby the escaping lubricant from the end of this bearing is lead through a space between the main double bearing 11 and sleeve 71, this sleeve being pressed into the hub flange of the magneto fly wheel 32 and revolves 120 therewith. At the opposite end of this sleeve or tubing, the escaping lubricant is thrown into the cavity of a stationary oil ring 72 and is collected in a lower pocket 73 by gravity, from where it is lead outside of the magneto through a small tube 74, 125 there to be disposed of as desired, or returned to the crank case. In order to properly cool the engine, the magneto fly wheel 32 is provided with vanes 75 which are adapted to blow air against the cylinder wall. In order to properly dissipate 130 the heat, the cylinder 12 is provided with heat radiating ribs 76.

In order to secure proper ignition of the combustible mixture in the cylinder, a high tension fly wheel magneto is provided. This magneto 135

consists of two main assemblies; namely the armature plate assembly and the fly wheel assembly. The armature plate 77 is provided with a clamp 78 and fastened on the main bearing 11, the plate 5 being located by the stop shoulder 79 on this bearing. This armature plate 77 is held stationary in timed position by a lug 80 and interlocking groove intermediate lugs 81 on the main bearing 11. The interrupter or breaker assembly 82 is fastened to the armature plate 77 with the breaker points 83 on the upper side, this construction being for the purpose that any lubricant which may pass along the bearings and lodge on the interrupter, will not collect on the breaker points, but in the lower portion of the breaker assembly. An adjusting screw 83^a permits adjustment of the lower point, while a governor 84 is provided with means for adjusting the speed of rotation and the frequency with which breaker 10 points 83 are opened.

The adjustment for opening of the breaker points is accomplished on the governor 84 by a long set screw 85 having a lock nut 86. This long set screw is easily accessible after the inspection plate 87 has been removed. The governor 25 is further furnished with an adjustable tension screw 88 provided with a lock thumb nut 89, the screw having attached thereto a spring 90 anchored on lug 91. The arrangement of the governor and the breaker arm of the breaker points 30 is such that they will cause the magneto to generate a hot spark in but one direction of rotation of the fly wheel. Likewise the engine will operate in but one direction.

35 The governor is thus provided with two adjustments, one for speed and the other for positioning the cam on the governor so that it properly engages the interrupter and opens the breaker points when necessary. The plate 87 allows for the ready 40 adjustment as desired.

The armature or mounting plate 77 supports a high tension coil 92, interrupter or breaker assembly 82 and condenser 93, the latter being connected thereto by means of a bracket 94. The 45 high tension coil is located in a recess of the armature or mounting plate, the purpose of this coil being to change magnetic energy into electric current and to intensify it into a magnitude capable of developing a hot spark at the spark 50 plug of the engine. The coil is provided with a primary and secondary winding, the primary winding or coil being wound over a laminated iron core and charged by a permanent magnet located in the fly wheel. At each revolution of 55 the fly wheel a weak electric current is induced in the primary coil, a part of the current being stored in the condenser 93.

60 The breaker or interrupter 82 is connected into the circuit of the primary coil so that the circuit is broken at every revolution of the fly wheel, and at the instant when the largest volume of magnetic flux passes through the iron core. Through the sudden interruption of the primary 65 circuit and the stored electric energy in the condenser, the high tension electric current is induced in the high tension coil which is wound directly over the primary coil, and which is connected in the high tension circuit. One end of this high tension coil is grounded and the other 70 is lead through the insulated connection socket in the dome 95 and through the high tension cable 96 to a spark plug 97 in the engine.

75 The interrupter or breaker assembly 82 is mounted on lugs 98 cast on the armature or mounting plate and attaching means 99, to bring

the breaker cantilever 98^a in the path of the cam of the governor. This breaker cantilever is pivotally mounted on a stud pin on the interrupter bracket 101 and is provided with a breaker point 83 on one end and a curved end on the other. The 80 interrupter or breaker cantilever 98^a is operated by a governor pin which strikes the curved end and is returned to normal position by a spring 102. The interrupter bracket also holds a bracket 103 having a blade or plate 100 which is insulated from the other half of the breaker, this blade or plate holding the other breaker point 83 which is adjustable by means of the adjusting screw 83^a. To this blade or plate leads a connection from one end of the primary coil and the connection from one side of the condenser, the other side of the condenser being grounded, as 85 shown at 104.

90 All of the working parts of the magneto are housed within the large concave center portion of the fly wheel. This includes the governor lever assembly 84 which is of the cantilever type and oscillates on a shoulder stud bolt 105 screwed into the fly wheel hub, which stud bolt also serves as a part fastening means of the fly wheel to the 95 coupling disc 34. The nut on the threaded portion of this stud pin serves as a locking means for the stud and fastening means for the fly wheel.

100 The arm 106 of the governor is shorter, and is provided with a cam pin 107 which strikes the curved end of the cantilever or the interrupter 82. Through a tapped hole of the longer arm 108 of the governor passes the long set screw 85 for adjusting the governor into proper position with the interrupter lever and to hold it in adjusted 105 position by taking its footing against the sleeve 71 and by being locked with the lock nut 86 against the governor arm. The same side of the governor 110 is also furnished with the tension screw 88 for speed adjustment.

115 Locking means of the thumb nut 89 is accomplished by a wedge shaped rib on the contact end of the nut with the lever, and slipped into a corresponding slide in the governor arm and is held interlocked by the action of the governor spring 90. 120 An opening is provided in the fly wheel in the immediate proximity of the adjusting screws of the governor, allowing for inspection of the magneto and for making the necessary adjustments possible. The thumb nut 89 provides for speed adjustments.

125 Inside of the concaved portion of the fly wheel and rotatable therewith, is mounted an arcuate permanent magnet 109 provided with pole shoes 110 and 111, which act on the iron core 112 of the 130 primary of the induction coil 92 through the laminated arm blocks 113 and 114.

135 The speed of rotation of the engine is governed by the frequency of the spark which in turn is governed by the governor in the fly wheel magneto. The engine may be stopped either by shutting off the supply of gasoline on the carburetor or by pulling the switch 115 by means of the rod 116 against the spark plug.

140 While the engine is shown as adapted for use with a washing machine, it is of course to be understood that the same may be used wherever a small independent power plant is desired. The simplicity and efficiency of the engine will be readily seen and appreciated from the above disclosure. The constructions of the governor and interrupter lever will not allow the engine to run backwards. This is accomplished by the round cam on the governor acting on an abrupt dent 145 in the interrupter lever, thus opening the breaker 150

points for a moment at the time when the greatest amount of magnetic flux flows through the core of the coil and when the piston of the engine is approximately at its upper power stroke, and only

5 when the engine is operating in the proper direction. When it is attempted to operate the engine in the opposite direction, the breaker points are opened when no magnetic flux passes through the core and thus no primary nor secondary current is induced.

Having thus disclosed the invention, I claim:

1. An accelerating device for internal combustion engines comprising a support, a gear segment pivotally mounted on said support, a piv-

15 oted actuating lever connected with said segment, a pinion constructed and arranged to be rotatably mounted on the crank shaft of an internal combustion engine in such position as to mesh with said segment, overthrew clutch means

20 constructed and arranged to operatively connect said pinion and said crank shaft, means normally acting to yieldably hold the segment in retracted position out of engagement with said

25 pinion, and a rectilinearly movable tooth slidably and yieldably mounted on one end of said segment in operative relation with respect to the other teeth of the segment and in such position as to be the first tooth of the segment to engage said pinion when said segment is moved in

30 opposition to said holding means.

2. An accelerating device for internal combustion engines comprising a support, a gear segment pivotally mounted on said support, a pivoted actuating lever connected with said segment, a pinion

35 constructed and arranged to be rotatably mounted on the crank shaft of an internal combustion engine in such position as to mesh with said segment, overthrew clutch means constructed and arranged to operatively connect said pinion and said crank shaft, means normally acting to yieldably hold the segment in retracted position out of engagement with said pinion, and a rectilinearly movable tooth

40 slidably and yieldably mounted on one end of said segment in operative relation with respect to the other teeth of the segment and in such position as to be the first tooth of the segment to engage said pinion when said segment is moved in opposition to said holding means.

and said crank shaft, means normally acting to yieldably hold the segment in retracted position out of engagement with said pinion, fixed members carried by one end of the segment, a rectilinearly movable tooth member slidably engaging said end and having longitudinal slots complementary to said fixed members, and means for yieldably projecting the tooth member to such an operative position with respect to the other teeth that it will be the first tooth of the segment to engage said pinion when the segment is moved in opposition to said holding means, said fixed members limiting the slidable movement of said tooth.

3. An accelerating device for internal combustion engines comprising a support, a stub shaft mounted in said support, a gear segment pivotally mounted on said stub shaft, an actuating lever also pivotally mounted on said stub shaft and movable with respect to the segment, complementary abutment members carried by the segment and the shaft and so constructed and arranged as to limit relative movement thereof, a pinion constructed and arranged to be rotatably mounted on the crank shaft of an internal combustion engine in such position as to mesh with said segment, overthrew clutch means constructed and arranged to operatively connect said pinion and said crank shaft, means normally acting to yieldably hold the segment in retracted position out of engagement with said pinion, and a rectilinearly movable tooth

45 slidably and yieldably mounted on one end of said segment in operative relation with respect to the other teeth of the segment and in such position as to be the first tooth of the segment to engage said pinion when said segment is moved in opposition to said holding means.

CERTIFICATE OF CORRECTION.

Patent No. 1,973,218.

September 11, 1934.

JOHN MIKULASEK.

It is hereby certified that error appears in the printed specification of the above numbered patent requiring correction as follows: Page 2, line 32, for "edgewise" read wedgewise; and line 108, for "magnet" read magneto; page 4, line 92, strike out the word "as"; and that the said Letters Patent should be read with these corrections therein that the same may conform to the record of the case in the Patent Office.

Signed and sealed this 9th day of October, A. D. 1934.

Leslie Frazer
Acting Commissioner of Patents.

(Seal)
